Primary Examiner — John Windmuller*Assistant Examiner* — Steven J Czyz(74) *Attorney, Agent, or Firm* — Tutunjian & Bitetto, P.C.**CLAIM**

The ornamental design for a box for dental tools, as shown and described.

DESCRIPTION

FIG. 1 is an exploded view of a box for dental tools, showing my new design;

FIG. 2 is a perspective view of the box for dental tools, shown in a compact state;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the article that form no part of the claimed design.

1 Claim, 5 Drawing Sheets(56)
